UNITED STATES PATENT OFFICE

135,469

DESIGN FOR A CHILD'S FOLDING TOILET SEAT

Pearl E. Dunn, Oakland, Calif.

Application July 12, 1941, Serial No. 102,109

Term of patent 3½ years

To all whom it may concern:

Be it known that I, Pearl E. Dunn, a citizen of the United States, residing at Oakland, in the county of Alameda and State of California, have invented a new, original, and ornamental Design for a Child's Folding Toilet Seat, of which the following is a specification, reference being had to the accompanying drawing, forming part thereof.

Figure 1 is a plan view of the toilet seat in

extended or flattened position, showing my new design;

Figure 2 is an edge-on view of the seat when folded; and

Figure 3 is an isometric view of the seat set up for use.

I claim:

The ornamental design for a child's folding toilet seat, as shown.

PEARL E. DUNN.
